CLAIM

The ornamental design for a connector, as shown and described.

DESCRIPTION

FIG. 1 is a perspective view of front, top and left side of a connector showing our new design;

FIG. 2 is a perspective view of from, top and right side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a cross sectional view thereof in the direction of Line 9-9 in FIG. 5.

The drawings include a separation which represents a symbolic break in length of the connector. The appearance of any portion of the article between the break lines forms no part of the claimed design.

The broken line portion of the figure drawings is included to show portions of the connector that form no part of the claimed design.
